UNITED STATES PATENT OFFICE.

ALICE G. MUNYON, OF SAN FRANCISCO, CALIFORNIA, ASSIGNOR OF ONE-THIRD TO
ELIZABETH M. BUTLER, OF SAN FRANCISCO, CALIFORNIA, AND ONE-THIRD TO
JOHN P. CARR, OF OAKLAND, CALIFORNIA.

COMPOSITION FOR REMOVING PAINT AND VARNISH.

No Drawing.

Application filed July 14, 1924. Serial No. 725,836.

This invention relates to a composition of matter for removing paints, varnishes and the like from various materials.

The primary object of the invention is to provide an improved composition which will more readily and perfectly remove paint, varnish and like stains, and to a process for manufacturing such a remover, which is simpler and more efficiently carried out than those heretofore used.

Another object of the invention is to provide an improved paint and varnish remover of a consistency of preferably a heavy syrup which can be applied with a brush and therefore easily removed with a sponge or by playing a hose thereupon.

Another object of the invention is the provision of an improved and simple process for manufacturing a paint and varnish remover, such process requiring no heating and comprising simply the thorough dissolving and mixing of certain ingredients in cold water to form a syrup-like solution.

With the above and other objects in view, my invention consists in the novel product herein defined and the novel method of producing such product. It should be understood, however, that while I have herein defined one specific method for carrying out my invention, such method can be varied as defined in the appended claim.

The several ingredients which may be used are as follows, but it will be seen that all of such ingredients are not essential to the practicing of my invention:

Three pounds potassium hydrate,

One pound ammonia,

One-half pound corn starch,

Three quarts of water,

One-half pound of ether,

Three ounces of citronella,

Three teaspoonsful of burnt sugar.

Briefly my improved method, in its preferred form, is as follows:

I thoroughly dissolve three pounds of potassium hydrate in one-half gallon of cold water. I dissolve one-half pound of starch, preferably corn starch, in one quart of cold water. I then combine these two solutions, at the same time stirring the same rapidly

for about two minutes to assure a thorough mixing thereof. Into this product I add one pound of ammonia (preferably about 12½ per cent) and stir sufficiently to thoroughly mix the entire ingredients together. The resulting product will be a heavy syrup-like solution which will most efficiently remove paint, varnish and other stains in the manner hereinafter described.

It may be desirable for various purposes to add other ingredients to the last named resulting product. For example, it is known that ether has a beneficial preserving action upon wood surfaces, and for this purpose therefore one-half pound of ether may be added if desired. Also, three ounces of citronella and three teaspoonsful of burnt sugar may be added to the solution to give the same a desirable odor and color, respectively.

As above stated the product in its final and usable form is preferably of a heavy syrup-like consistency. This form of the product is advantageous for various reasons. Primarily among these is its easy application in use. This operation is very simple and consists of merely applying the syrup with a brush to the surface to be treated. This coating should be permitted to remain on the surface for about thirty minutes, during which time it acts on the paint or varnish to dissolve and absorb the same. The syrup can thereafter be easily removed with a sponge or by playing a hose thereupon. When thus removed the surface will be found to be entirely free from the objectionable stains. It may furthermore be stated that in its liquid form the remover can be easily bottled and placed in salable condition.

Having thus described my invention, what I claim and desire to secure by Letters Patent is—

A composition for removing paint and varnish, consisting, approximately three pounds of potassium hydrate, one pound of ammonia, one-half pound of corn starch, one-half pound of ether, and three quarts of water in solution.

ALICE G. MUNYON.
